POURING SPOUT STRUCTURE FOR CARTONS

Henry F. Phillips, Oakland, Calif., assignor, by direct and mesne assignments, to Floseal Corporation, a corporation of Delaware

Application May 24, 1952, Serial No. 289,838

2 Claims. (Cl. 229—17)

This invention relates to pouring spout structure in cartons and has for one of its objects the provision of a pouring spout that is readily movable from a position in which the dispensing spout is closed, to fully open pouring position and vice versa, and which spout will stay in said pouring position without the necessity for employing locking notches and tabs or the equivalent.

Another object of the invention is the provision of a spout in a carton, which spout is readily movable from a position in which the dispensing opening is closed toward fully open position at any desired degree of extension of the spout from said opening to enable the user to control the rate of flow of material from said carton.

A still further object of the invention is the provision of pouring spout structure in a carton that enables the user to easily withdraw the spout from the dispensing opening that is normally covered by the spout, without injury to the carton or spout.

Another object of the invention is the provision of a way of forming a carton from cardboard in which a glue flap and one of the carton walls are formed to cooperate for forming pouring spout structure so that freedom of the spout for opening and for closing will be insured at no noticeable added expense to the carton, and at the same time a secure seal of the dispensing opening will be effected when the spout is closed.

In explanation of the foregoing objects, heretofore in the formation of pouring spouts, it has been customary to crease the spout carrying layer of the material along the folding line or lines to facilitate bending, and in order to provide a closure for the dispensing opening from which the spout is drawn, such closure usually is secured to the spout for movement therewith.

The difficulty with this structure has been that the initial opening of the spout has heretofore required so much force that the closure layer in many instances has been torn or pulled away from the spout, thus making it impossible to withdraw the spout, and once the spout is pulled to open position, assuming the withdrawal has been effected without injury to the spout, the spout will automatically spring back to almost closed position due to the tension in the material along the fold lines.

By the present structure, and whether the spout is of the double wing type with a flat bottom or is of V-shaped cross sectional contour, the withdrawal of the spout is made much easier than in prior structures, and the spout will stay open when released, or will stay in any desired degree of extension from the carton.

Also, one of the factors that has heretofore contributed materially to the difficulty of initially moving the pouring spout to pouring position has been the problem of gluing the pouring spout to the closure for the dispensing opening with sufficient accuracy to make a good bond and yet not to glue the spout to an adjoining fixed part of the container. If the bond is not over a sufficient area the closure (which usually pulls the spout with it) is readily pulled away from the spout rendering it difficult, if not impossible, to withdraw the spout, and if the

2

spout is accidentally glued to a fixed part of the container wall, the same thing occurs.

With the present invention, provision is made to insure a proper and extremely accurate gluing together of localized parts of the spout structure without regard to precision in the glue applicator device, and at no noticeable added expense. In other words, no exact "spotting" of the glue is required. When the spout is on a glue flap of the container, the carton may be printed in the conventional manner and then the glue may be applied to the glue flap that carries the spout without regard to the spout, and after the glue flap is glued in the usual manner to the carton blank to form the carton, the spout will stick only in those exact places where it must stick in order to make the spout structure operative.

Another object of the invention is the provision of a substantially V-shaped pouring spout in a side wall of a carton, and which structure does not weaken the side wall and the carton can be filled with material to substantially the top of the carton, thus effecting a substantial saving in the material of the carton over those structures that make provision for cutting out a dispensing opening along the upper edge of the carton.

The principal objection to V-shaped pouring spouts has been the difficulty in opening them and in keeping them open without using some kind of a notch in the spout for engaging a part of the carton at or adjacent to the dispensing opening. This has already been mentioned as being an objection that is found to be general, even where the double wing spouts having a flat bottom are used, but it is particularly noticeable in spouts that are V-shaped in cross section and that are not corner spouts, but that are spaced from the corners of the carton, and that are in a side wall.

With the present invention provision is made for a spout of V-shaped cross section to be in a side wall of the carton and spaced below the top of the latter and which spout does not weaken the carton and is easily and quickly moved to and from pouring position and in said structure provision is made for securely and directly engaging the spout itself in the initial and subsequent operations of moving it to pouring position, thereby completely avoiding the possibility of rendering the spout inaccessible for withdrawal by accidental mutilation of the spout structure.

Other objects and advantages will appear in the description and in the drawings.

In the drawings, Fig. 1 is a plan view of a blank from which a carton having the present pouring spout is adapted to be formed. The side shown is the side that will be the inside of the finished carton.

Fig. 2 is an enlarged, fragmentary elevational view of the outer layer of a side wall of the carton, showing the closure to which the spout is adapted to be secured for movement with the spout.

Fig. 3 is an enlarged fragmentary elevational view of the spout to which the tab of Fig. 2 is attached, the spout being shown in the position in which it would normally be below the closure of Fig. 2.

Fig. 4 is an enlarged fragmentary elevational view of the closure and spout of Figs. 2, 3 in assembled relation when the ends of the blank of Fig. 1 are folded on each other with the closure of Fig. 2 outermost.

Fig. 5 is a fragmentary elevational view of the spout of Fig. 4 in substantially fully open pouring position.

Fig. 6 is a sectional view taken along line 6—6 of Fig. 5.

Fig. 7 is an enlarged elevational view of the spout structure as seen from the opposite side of the blank shown in Fig. 3.

Figs. 8, 9 are views that are similar to that of Fig. 3,

but respectively showing slight modifications of the form shown in Fig. 3, and

Fig. 10 shows a slightly modified form of the structure of Fig. 3.

In Fig. 1 the blank for forming the carton will be seen to comprise four spaced parallel folding creases 1, 2, 3, and 4 starting from the right side as seen in said figure. The side walls of the carton to be formed are designated 5, 6, 7, 8 starting from the right and said creases form the junctures between said side walls. Folding flaps 9 at the upper ends of said side walls are adapted to be folded one on the other in the usual manner to provide the closed upper end of the finished carton, and folding flaps 10 at the lower ends of said side walls are adapted to be similarly folded to form the bottom wall. Folding crease 11 defines the junctures between the folding flaps 9 and the side walls, while folding crease 12 defines the junctures between flaps 10 and said side walls.

In extension of the side wall 8 and integral therewith is an extension or glue flap 13, its juncture with side wall 8 being defined by the folding crease 4, and when the carton is formed said extension underlies the side wall 5 that is at the other end of the blank.

Preferably, the upper end 14 of glue flap 13 is of substantially the same width as wall 5, and below said upper end the glue flap is cut away so that only a narrow strip 15 extends along crease 4. Tabs 16, 17 extending above and below creases 11, 12 from said glue flap 13 and adjacent to the ends of crease 4 will be folded over in lapping relation to the other folding flaps 9, 10 when the carton is formed.

As has already been mentioned, Fig. 1 shows the blank from the side that will be the inside of the carton when the latter is formed. In forming the carton the side wall 5 and glue flap 13 will be brought toward the viewer and placed in lapping relation to each other with glue flap 13 underlying wall 5 so as to provide an inside wall and with glue flap 13 and said wall 5 in opposed relation to wall 7. The glue flap 13 is to be glued to wall 5 along strip 15 and at the upper end 14 as will later be explained more in detail.

In Figs. 2, 3, the wall 5 and the upper end 14 of glue flap 13 are shown in the positions they would occupy when the wall 5 and glue flap 13 are in said lapping relation, except that they are shown separate from each other. Fig. 4 shows them together.

The outside wall 5 is formed to provide a generally triangular, sector-shaped portion 19, the straight radial edges 20, 21 of which extend divergently upwardly at an acute angle from meeting relationship at their lower ends, while the upper edge 22 extends arcuately about a point disposed at the meeting ends of edges 20, 21 as a center.

The edges 21, 22 are cut through the wall 5 except at tack point 23 that is along edge 21 close to the upper end of the latter.

The marginal portion of the wall 5 along the edge 22 above portion 19, and adjacent to the upper end of edge 21 is formed with a recess 24 that opens to edge 22. The length of this recess linearly of edge 22 and its depth are sufficient to provide for access of the nail of a finger to the upper edge of portion 19 and also the portion of the spout that is adapted to underlie said portion 19. This will be described more in detail later on.

Edge 20 of portion 19 is defined by a folding crease or score 20. Thus upon pulling the part 19 outwardly of wall 5 by means of a finger engaging the spout close to the tacking section 23, the portion 19 will readily be broken and it will swing outwardly relative to wall 5 about crease 20.

The upper end 14 of glue flap 13 (which end will be generally called the "extension" in referring to it hereafter unless specifically referred to as the upper end thereof or as the inside wall) is formed with a continuous line of severance that defines the outline of a flat spout-forming closure generally designated 25 hav-

ing outer and inner wings 26, 27 that are bendable along a row of slots or fold line 28 that divides the closure spout into said wings that, in turn, will form the two sides of the generally V-shaped spout shown in Figs. 5, 6. Rows of slots 28, 29 define two edges of the sector-shaped generally triangular inner wing 27, which rows are substantially coincident with the edges 21, 20 respectively of the triangular portion 19 in wall 5, except that the row 28 may be just a trifle offset toward row 29 with respect to the edge 21.

The arcuately extending free edge 30 that extends between the upper ends of row 28, 29 is developed about a slightly shorter radius than edge 22 of portion 19, therefore marginal portion 33 (Fig. 5) along edge 30 will be overlapped by the marginal portion 34 along edge 22 (Fig. 4). The portion 19 and wing 27 are glued together so that the spout 25 will move with the portion 19 (bending along rows 28, 29) and through the generally triangular opening in wall 5 that is normally closed by portion 19.

The end of edge 30 adjacent to the upper end of row 28 extends slightly upwardly as at 35 (Fig. 3) to meet an extension of the line on which row 28 is disposed, at point 36, and then edge 37 continues from said point along a curved line that is substantially developed about the meeting point of rows 28, 29, but of progressively increasing radius as it approaches the end 38 of the outer way 26 that is remote from the row 28. The lower edge 39 extends back to the lower ends of rows 28, 29. The position of the edge 35 results in said edge cooperating with the edge of the wall 5 at the upper end of edge 21 of portion 19 to form a notch in which the upper edge of the wing or portion 26 of the spout is held during movement of the spout to and from pouring position. Thus wing 26 will be held against the edge of the opening provided in wall 5 when portion 19 is swung outwardly to prevent any likelihood of leakage of material past the outer side of said wing. When the spout is retracted into the carton and the closure portions 19, 27 again close the openings from which they were moved, the carton will be effectively closed because of the overlapping of marginal portion 34 over marginal portion 33, and the slight overlapping of the slots 28 by the marginal portion of part 19 along edge 21 of the latter.

The spout will resist complete withdrawal out of the carton due to the increased radius of edge 37 at the end 38.

One of the highly important features in this invention is the provision of slots 28, 29. Heretofore one of the principal objections to spouts formed from the material of the cartons, or as cardboard inserts, has been the fact that the spout is accidentally torn or mutilated the first time it is used due to the difficulty of loosening or freeing it for withdrawal. For example were scores or creases employed instead of slots 28, 29, the part 19 would tend to be torn and to be separated from the portion 27, and this would also be the case if edge 21 were perforated instead of being merely tacked to the wall 5 at point or points 23.

Heretofore, and particularly where spout structures in cartons have employed folding creases or scores, or have relied upon bending the spout, as in U. S. Letters Patent to Ringler, No. 2,358,659 of September 19, 1944, the spout must be locked in open position or it will automatically return to substantially closed position as soon as the force that has pulled it out has been released. The provision of means for locking the spout in any position usually results in restricting the position of the spout to one pouring position only, and furthermore, the locking means is usually ineffective after one or two withdrawals of the spout due to wear and abrasion, and in other instances the resistance necessary to overcome the locking force in either locking or unlocking the spout is so great as to result in injury to the spout.

By providing slots 28, 29 which are open and elongated longitudinally of the rows a greater distance than

the spaces between slots and by having the end slots of the rows extend from substantially the meeting ends of the row to the edge 30, the tension that is left in the material along said rows is reduced (after bending along said rows) to the point where the bending along said rows is easily and readily accomplished, and the spout will stay in substantially any degree of extension, instead of retracting into the carton. Furthermore, the material left between perforations will not break, but will hold the parts 26, 27 together until the carton is empty, and longer if desired.

The width of the slots is important, as it should not be greater than the thickness of the material. As soon as the parts 26, 27 bend along the line of slots 28 to the position shown in Fig. 5, the slots are closed, so no possible leak can occur. Slots 29 are, of course, covered by the part 19 along crease 22.

In order to enable a person to pull the spout of the carton to pouring position without tearing the part 19 from the portion 25 of the spout, provision is made for engaging the upper marginal portion 33 of the spout by the nail of a finger.

To accomplish this, the marginal portion of the extension 14 above and along edge 30 is formed with a pair of relatively short slits 45, 46 that extend generally perpendicularly relative to edge 30 and to the line of severance of the spout closure.

As seen in Figs. 3, 4, these slits preferably commence along edge 30 at points slightly outwardly of but relatively close to the ends of recess 24. Thus when the nail of the finger presses against the portion 44 of extension 14 that is between slits 45, 46 and at a point close to edge 30, as is normally done in engaging the spout, the said portion 46 may be bent inwardly into the carton sufficiently to enable the nail of the finger to engage the inner side of the margin 33 of said spout instead of merely engaging the material portion 34 of the part 19. It should also be noted that the positioning of the slits 45, 46 oppositely outwardly of the ends of the recess 24 positions them behind the outer wall 5 of the carton so that said slits are covered or sealed by said outer wall.

If it were not for slits 45, 46, or their equivalent, the spout would not be engaged by the nail, but instead, the part 19 would be engaged.

In some instances, it is found desirable to have the slits, designated 47, 48 in Fig. 8, terminate just short of the edge 30, leaving the portion 49 lightly tacked to the extension 14 at points 50 by short readily breakable sections, and in still other instances, it has been found desirable that slits, designated 60, 61 in Fig. 9, extend to edge 30, the same as in Fig. 5, but that additional spaced perforations or slits 62 be formed in the extension 14 in continuation of the closed ends of slits 60, 61. These perforations or slits 62 are preferably relatively close together so that only a small force against the portion 64 between slits 60, 61 is required to break the connections between these slits.

The character of the material of the container and the size of the container and spout structure will dictate which form is most suitable, although in most instances the form shown in Fig. 3 is satisfactory, or even one slit will suffice.

The gluing of the extension wall 14 to the side wall at the opposite end of the row that form the side walls of the carton is an operation that heretofore required accuracy so great that seldom was the result perfect.

In the present instance, upon printing the outer surface of the blank with the data identifying the contents, the outer surface of the wing 26 in the form shown in Figs. 1 to 10 are also imprinted with the printer's ink as indicated by the vertical line shading in Figs. 3, 8, 10, and the ink imprint may extend slightly across the free edges of the wings on to the material surrounding the wings and across the row of slots 28. This is clearly seen in Fig. 3. At the same time the portion of the wall

14 that lies between slits 45, 46 (Fig. 3) and are imprinted to the edge of the wall 14.

In the structures of Figs. 3, 8, 9 and 10, this last imprinting of the wall 14 covers a greater area than the recess 24 and extends to the edge 30, but a slight space 85 is left between each of the slits 45, 46 or the similar slits in Figs. 8, 9 and the imprinted area.

Where conventional printing ink or pigment bearing imprinting material such as para red and others is used, we have found that the conventional glue used in the manufacture of cartons will not stick to said ink or imprinting material. Thus the application of glue to the outer surface of the extension 14 and over the imprinted portions will be very accurately restricted to the unprinted part and the spout portion 27 will be glued to the closure part 19, but no portion that has the imprinting thereon will stick to wall 5.

The slits 45, 46 and similar slits in Figs. 8, 9 will be sealed by reason of the glue along opposite sides of said slits, but the amount of glue deposited between the slits and the imprinted portion between them is so small that the seal is easily broken when pressure is applied against the imprinted portion.

It has also been found that any suitable penetrating agent in the ink, such as is in para red, will so impregnate the cardboard that glue will not stick to either side nor to the edges of the slots 28, nor the edges of the wing 26, thus insuring freedom of operation of the spout heretofore not obtained and the glue applicator can apply glue to any portion and to either side of glue flap or extension 14 without making the spout inoperative.

While printer's ink adapted to penetrate the cardboard is preferable because of the fact that the imprinting of the areas to be free from glue can be done at the same time the printing operation is performed and with the same ink, it is obvious that any other suitable glue repellent material capable of being similarly applied and meeting with the requirement of the law may be employed and the term, "glue repellent material" is intended to cover any such materials, and insofar as has been found any penetrating imprinting material that does not have an affinity for glue when applied to cardboard or to the flexible material from which the container is formed would be suitable.

As heretofore mentioned, it is not always necessary that two slits, such as 45, 46 be used, inasmuch as substantially all of the area between the slits and extending from the free edge of the wall 14 to the edge 30, is unsecured to the wall 5. The two slits are preferable where the cardboard is relatively heavy and stiff, but satisfactory results can be had with the use of only one slit in lighter and softer board, and in certain instances fair results can be had without the use of the slits, but at least one should be used to facilitate obtaining proper access to the spout.

In many instances it has been found that the wing 26 (Fig. 3) does not readily free itself along its cut edges from the remainder of the stock along said edges. This circumstance is most prevalent where the cardboard is of medium and cheaper grades. While it is relatively simple to form adequate slots 28, 29 to facilitate bending of the spout wings along the lines of such slots, it is another thing to completely free the wings 26 from the remainder of the stock, particularly in the cheaper stock. The fibers remain uncut and bind the spout flaps to the remainder.

The above objection is overcome by creasing the wing 26 along lines 90, 91 (Figs. 1, 3, 6 and 7 to 10). The crease 90 extends across the wing 26 from point 94 along edge 37 which is about where the edge 37 becomes progressively farther from the point of intersection of rows 28, 29, to the said latter point, or from a point along edge 39 close to said intersection. The crease 91 extends across the wing 26 along but spaced from edge 37, commencing at one end along row 28 near point 36 and end-

ing at a point along crease 90. These creases draw the portion of the wing between them and the outer edges of the wing away from the stock surrounding the wing a sufficient distance to free the edges 37, 38, 39 from the surrounding stock thereby enabling the wing to freely bend along the line of slots 28 when the spout is drawn to pouring position.

In the large sized cartons where there is ample room, the stock of extension 14 may be cut away as at 95 around the wing 26 from points spaced along edges 37, 39 from the point 36 and the intersection of rows of slots 28, 29 instead of using the creases to draw the material of the wing away from the surrounding material of the extension.

While the structure as shown and described is indicated in parts of the carton that are integral with the carton walls, it is obvious that similar structure could be used on inner and outer layers of sheet material adapted to be secured to one of the carton walls over an opening in the latter of suitable size for swinging the spout therethrough. The crease 90 (Fig. 3) is straight and is positioned on the wing 26 so that it will be aligned with and in yieldable engagement with the adjacent edge of the opening in the outer wall 5 when the spout is pulled through such opening, thereby providing resistance to any tendency of the spout to spring back into the carton.

I claim:

1. A carton having an outside wall cut to provide a generally triangular sector shaped flap formed with an acute lower angle and hinged along one of its downwardly extending sides to swing outwardly to provide an opening, said wall being cut away adjacent the upper edge of said flap to provide a finger opening, an inside wall secured to and against the inner side of said outside wall relative to the inside of said carton and having a continuous line of severance forming a flat spout-forming closure supported along a hinge line coincident with the hinge line of said flap for swinging through said first mentioned opening, said closure having a fold line substantially aligned with the other side of said acute angle dividing said closure into an outer and an inner wing, said inner wing being in lapping relation to said flap and secured thereto, said outer wing being in lapping relation to but free from the part of said outside wall along said other side of said acute angle, said line of severance extending from said hinge line over said triangular flap along and spaced slightly below the upper edge of said flap that is opposite to said lower angle and continuing around said outer wing for defining the edges thereof, said outer wing being movable through the opening defined by said triangular flap with its side that is adjacent to said outside wall slidably against the edge of said last mentioned opening that is opposite to said hinge line, and a crease extending across said outer wing coincident with said last mentioned edge when said outer wing is moved through said last mentioned opening for engage-

ment with said last mentioned edge to thereby releasably hold said spout forming closure in pouring position extending through said last mentioned opening.

2. A carton having an outside wall cut to provide a generally triangular sector shaped flap formed with an acute lower angle and hinged along one of its downwardly extending sides to swing outwardly to provide an opening, an inside wall secured to and against the inner side of said outside wall relative to the inside of said carton and having a continuous line of severance forming a flat spout-forming closure supported along a hinge line coincident with one side of said acute angle for swinging through said opening, said closure having a fold line substantially aligned with the other side of said acute angle dividing said closure into an outer and an inner wing, said inner wing being in lapping relation to said flap and secured thereto, said outer wing being in lapping relation to but free from the part of said outside wall along said other side of said acute angle, said line of severance extending from said hinge line over said triangular flap along and spaced slightly below the upper edge of said flap that is opposite to said lower angle and continuing around said outer wing for defining the edges thereof, said outer wing being movable through said opening defined by said triangular flap upon swinging said inner wing through said opening about said hinge line, said outside wall only adjacent the upper edge of said flap being cut away to provide a finger receiving recess, the lower edge of said recess being defined by the upper edge of said flap, a pair of slits formed in said inside wall spaced outwardly from opposite sides of said recess and extending to said line of severance with the part of said inside wall between said slits extending across said recess, thereby freeing the material of said inside wall between said slits and along said line of severance for being sprung inwardly under the pressure of a finger engaging the upper edge of said triangular flap, said slits being below and covered by said outside wall whereby said outside wall provides a seal extending across said slits.
